UNITED STATES PATENT OFFICE.

ABRAM R. HALL, OF GREELEY, COLORADO.

OILER FOR DIE-STOCKS.

1,210,931.

Specification of Letters Patent. Patented Jan. 2, 1917.

Application filed June 29, 1916. Serial No. 106,693.

To all whom it may concern:

Be it known that I, ABRAM R. HALL, a citizen of the United States, residing at Greeley, in the county of Weld and State of Colorado, have invented certain new and useful Improvements in Oilers for Die-Stocks, of which the following is a specification.

This invention relates to an improvement in oilers for use with die stocks, and comprises a member having substantially the shape of one of the handles as usually fitted to a die stock, which member is adapted to be fitted in conjunction with the head of the stock so that it may have utility in the manual handling and use of the stock, and which at the same time is adapted to contain oil and to have parts associated therewith manually operated to supply this oil at proper intervals.

An object of my invention is to provide a device as set forth above which may be fitted in conjunction with the die stock as manufactured, or which may be sold as a separate attachment to be applied by the user, and which is so constructed that a considerable quantity of oil or other lubricant may be stored therein and can be supplied at just the proper points for the work being done, when the die becomes dry as it works upon the parts being threaded, this permitting continual use of the tool in cutting a thread of any length without the necessity of stopping the cutting and placing the lubricant at the proper point from the spout of an oil can or from some other independent source.

A further object lies in so constructing the device of the invention that air will be supplied to the lubricant storage chamber as the lubricant is discharged therefrom, thus relieving any tendency to the creation of a partial vacuum which would hold the oil or lubricant against proper flowing, and to further provide portions of a structure which will prevent leakage of the lubricant which is in a fluid state, either when the tool is being used or when it is being carried or is lying idle.

With the above and other objects in view, my invention consists in certain novel features of construction and combinations of parts which will be hereinafter set forth in connection with the drawings and then more particularly pointed out in the claims.

In the drawings: Figure 1 is a view in

side elevation of a handle having my invention embodied therein. Fig. 2 is a longitudinal sectional view through the structure as disclosed in Fig. 1.

A body 1, which is preferably of pipe of a standard diameter, either $\frac{3}{4}$ in. or $\frac{1}{2}$ in., such as is now generally used in making the handles of die stocks, is externally screw threaded at each of its ends as shown at 2 and 3. A head portion 4, which is preferably a casting, is cored out or bored so that the opening through the center thereof will be preferably formed to four different diameters. At one end, the head member 4 is internally screw threaded and this threaded portion is formed to be fitted over the screw threaded end 2 of the body 1 so that the body and head members will be rigidly secured together, and the diameter of the central bore of the head 4 immediately adjacent to the inner end of the body member 1 is made of the same diameter as the bore of the body to form a piston chamber 5, as will be hereinafter more fully set forth.

The end 3 of the body 1 is internally screw threaded and a face bushing 6 is removably fitted to close this end so that liquid lubricant may be placed in the bore of the body member 1 and then the screw threaded portion 3 of this body may be entered and screwed into one of the handle sockets of the usual die stock head. A valve casing 7 is secured through a screw threaded orifice 8 formed through the side wall of the body 1 adjacent to the inner end which is closed by the removable face bushing 6, and a ball check valve 9 is mounted in the casing 7 to be normally held by the spring 10 in a relation that incloses over the fluid passage 11 from the fluid chamber within the handle 1 to the interior of the valve casing. A tube 12 is passed through the central opening of the locking nut 13, which nut is screwed onto the valve casing 7 to connect the tube 12 therewith, and thus a passage is provided from the interior of the body member 1 and through the tube 12 to permit the supply of oil or other lubricant carried within the storage chamber within the body 1 to any desired point. By making this tube 12 of soft copper, or other suitable material, the exact disposition of the open discharge end thereof can be varied to suit the requirement of the particular die stock head to which the handle is fitted and consequently the lubricant can be supplied in such a re-

lation that it will flow directly into the threads as cut by the die and will lubricate the die, or the lubricant may be supplied on the pipe, bolt, or other member which is being threaded, in advance of the die so that it will have an opportunity to penetrate into the crevasses which are usually found on the outer steel like surface of pipes and like members.

10 The bore 13 at the outer end of the head member 4 is made of comparatively large diameter and the bore intermediate this handle receiving chamber 13 and the piston chamber 5 is made to be graduated between the two diameters, this intermediate portion forming an air supply chamber 14.

15 A removable face bushing 15 is mounted in the handle receiving chamber 13 to close access to the air supply chamber 14 except for the central orifice 16 formed through this bushing 15. A plunger stem 17 is mounted through the opening 16 and is arranged to be capable of reciprocatory movement therein, the stem 17 having a reasonably tight fit within the orifice 16. A flexible cup washer 18 is mounted around the inner end of the plunger stem 17 and the washers 19 and 20 are mounted on opposite sides thereof to give proper backing to the flexible washer 18 which is secured in place by a locking nut 21. By this arrangement of the cup washer and the supporting washers, a piston structure is provided which will give a washing stroke upon inward movement of the plunger stem 17. A handle 22 is mounted on the outer end of the stem 17 to work in the handle chamber 13, and has slight projection beyond the extreme outer end of the head member 4, the parts being thus so arranged that the handle 22 is normally in a position that it may be readily engaged by the thumb or finger and upon being depressed into the handle receiving chamber 13 will cause inward movement of the piston structure embodying the cup washers 18, thus exerting pressure within the lubricant chamber to expel a limited quantity of the lubricant passed the check valve 9 and through the tube 12 to discharge at the proper point adjacent to the die.

20 Washers 23 and 24 are mounted around the plunger stem 17 to bear against the inner side of the removable face bushing 15 and against the shoulder formed between the air supply chamber 14 and the piston chamber 5, and a coil spring 25 is mounted between these washers around the stem in such relation that as the plunger stem is moved inwardly the washer 23 will be brought to bear against the spring 25 and consequently the stem and the piston carried thereby will be returned to the normal relation as shown in Fig. 2 immediately the pressure upon the handle 22 is removed. With this operation 25 of the parts, the device will be efficient in

supplying lubricant, however, due to the fact that the check valve 9 closes the passage 11 against back flow of fluid through the tube 12, no air can find its way into the lubricant chamber within the body 1. If the parts be fitted sufficiently loosely that air will be permitted to seep back, then the oil or other lubricant will find its way out through these loosely fitted joints, and it therefore becomes advisable that some means be provided whereby air will be permitted to flow into the lubricant chambers to compensate for the displacement of the lubricant. With the above in mind, I provide a central bore 26 in the inner end of the plunger stem 17 which is made of sufficient depth that it extends in such a relation that a branch air supply passage 27 will be at all times in a position to open into the air supply chamber 14 of the head member 4. The locking nut 21 has a central opening therethrough in alignment with the bore 26, and a check valve 27 is mounted in the bore 26 to be normally held closed by the spring 28 to thus prevent the back flow of liquid lubricant into the air supply chamber 14. As has been stated, the plunger stem 17 has a reasonably loose fit through the removable face bushing 15, and in consequence air will be permitted to find its way through the space around the stem and into the chamber 14 and as the piston structure is returned under the tension of the spring 25 and the cubic volume of the lubricant chamber is thus increased, suction will be created through the bore 26 and the fluid supply passage 27 sufficiently strong to unseat the valve 27, and consequently air will flow into the lubricant chamber to compensate for the volume of liquid displaced by the instroke of the piston and upon the passage of sufficient air to give the proper compensation, the valve 27 will be again closed and thus the air supply passage will be cut off to prevent the flow of the liquid lubricant back through the supply passage 27 into the air supply chamber 14.

25 From the foregoing it will be seen that I have provided a structure which may be incorporated with a die stock head as the same is manufactured, or which may be constructed as a separate attachment to be applied to take the place of one of the handles of a standard die stock which is already in use, and that the structure is so arranged that a considerable quantity of lubricant in a liquid form may be stored therein and may be supplied in single drops or perhaps in some instances in a slow and steady flow by manipulation of the plunger stem 17, thus permitting the supply of just the proper quantity of lubricant and the placing of the same at the proper point, and while I have herein shown and described only one specific form of the device, it will be understood that 30

changes and variations might be resorted to in the form and arrangement of the parts without departing from the spirit and scope of my invention, and hence I do not wish to be limited to the exact disclosure but only to such points as may be set forth in the claims.

5 I claim:

1. A lubricator comprising a hollow body portion adapted to contain a liquid lubricant, a lubricant discharge passage from one 10 end of said body, a check valve to preclude return of the lubricant through said discharge passage, a plunger stem mounted at the remaining end of the body, a piston on 15 said plunger working to cause the flow of liquid lubricant through the discharge passage as the plunger stem is moved inwardly, and means to permit supply of air to the lubricant chamber upon the return stroke of 20 the piston to compensate for the liquid discharged from the chamber by the instroke of the piston.

2. A lubricator comprising a body portion formed to provide a lubricant containing chamber, a passage from said chamber, 25 a head member secured on said body member and provided with a bore alined with the liquid chamber in the body, a removable face bushing mounting in the outer end of said 30 head member and provided with a central opening, a plunger stem mounted to be capable of reciprocatory movement through the orifice of the bushing, a piston carried by the inner end of said plunger stem to cause 35 discharge of lubricant through the passage from the storage chamber upon instrokes of the plunger stem following instroke of the piston, a check valve mounted in the lubricant discharge passage to close the same against back flow of lubricant, an air supply chamber formed in the head, a valved air 40 passage formed through the plunger stem to open into the air supply chamber, and means held under the proper packing tension by said spring to close access from the lubricant chamber to the air supply chamber.

45 of the plunger stem, and a spring to return the plunger stem following instroke of the piston.

3. A lubricator comprising a body portion 50 formed to provide a lubricant containing chamber, a passage from said chamber, a head member secured on said body member and provided with a bore alined with the liquid chamber in the body, a removable face 55 bushing mounting in the outer end of said head member and provided with a central opening, a plunger stem mounted to be capable of reciprocatory movement through the orifice of the bushing, a piston carried by the inner end of said plunger stem to cause discharge of lubricant through the passage from the storage chamber upon instrokes of the plunger stem following instroke of the piston, a check valve mounted in the lubricant discharge passage to close the same against back flow of lubricant, an air supply chamber formed in the head, a valved air 60 passage formed through the plunger stem to open into the air supply chamber, and means held under the proper packing tension by said spring to close access from the lubricant chamber to the air supply chamber.

65 In testimony whereof I affix my signature in presence of two witnesses.

ABRAM R. HALL.
